WATER HEATER

Richard I. Gaines, Port Arthur, Tex.

Application June 9, 1943, Serial No. 490,128

6 Claims. (Cl. 122—17)

1

This invention relates to water heaters and has for its principal object to provide a heater structure in which the heat of a burner is applied to obtain substantially greater efficiency from a given amount of fuel.

Other objects of the invention are to provide a heater structure having a relatively large surface heated by radiation and by direct contact of hot gases of combustion; to provide an improved burner structure having radiants for spreading the flame of the burner relatively to the heating surfaces of the heater tank; and to provide a water heater with an interior burner chamber completely contained within the tank of the heater and connecting with a flue extending through the heater tank.

In accomplishing these and other objects of the invention, I have provided improved details of structure, the preferred form of which is illustrated in the accompanying drawings, wherein:

Fig. 1 is a perspective section through a water heater embodying the features of the present invention.

Fig. 2 is a fragmentary perspective view of the lower portion of the burner chamber.

Fig. 3 is a perspective view of the refractory element of the burner.

Fig. 4 is a perspective view of the gas distributing element of the burner.

Referring more in detail to the drawings:

1 designates a domestic type water heater constructed in accordance with the present invention and which includes a tank 2 having a preferably cylindrical wall 3 closed at the ends by top and bottom heads 4 and 5 to form a water chamber 6. The top head 4 is preferably welded to the upper portion of the wall 3 or otherwise connected to provide a leak-tight joint capable of retaining water under pressure. The bottom head 5 is inset within the lower end of the wall 3 and has an annular flange 7 welded to the inner face of the wall 3 to form a leak-tight joint.

Carried by the bottom head 5 and extending upwardly therefrom and inwardly of the tank is a burner compartment 8 that is formed by an annular wall 9 having a skirt 10 depending below the head 5. The wall 9 is of a diameter to provide a circulating space 11 therearound and the upper end connects with a flue 12 that extends upwardly through the tank and projects from the top head 4 to form a collar 13 thereabove. The collar 13 may be connected with a vent pipe 14 leading to a chimney or the like (not shown) for carrying of spent products of combustion and to establish an inflow of combustion supporting air to the burner chamber.

The tank thus described may be covered with a suitable insulating material 15 and enclosed in a jacket 16 as in conventional water heater construction. Water is admitted to the tank through

5 a pipe 17 extending downwardly through the top head 4 and terminating in the water space 11 that surrounds the burner compartment. The upper end of the pipe 17 projects through the jacket and connects by a fitting 18 which in turn is connected by a pipe 19 with a source of water service supply. Hot water is discharged from the tank through a pipe 20 that is connected by a fitting 21 with a nipple 22 attached to the top head 4.

10 The burner 23 includes a circular gas distributor 24 in the form of a hollow ring having a plurality of gas outlet orifices 25 in the upper face thereof. Formed on the top of the distributor and within the apertured portion of the ring is an annular ledge 26 that seats a radiant refractory element 27, later described. A combustible mixture is supplied to the distributor through a duct-like arm 28 having connection through a venturi 29 with an air and gas mixer 30, the mixer 30 being supplied with gas through a valve 31 under control of the usual thermostat 32, the specific form of which forms no part of the present invention.

15 The heat radiant element 27 includes a hollow cylindrical body 33 formed of refractory material and is closed at the upper end as at 34 and open at the bottom as shown at 35. The diameter of the body substantially conforms to that of the ledge 26 and when seated thereon, the flames from the burning gas play upwardly upon the circumferential surface of the refractory. In order to increase the efficiency of the refractory, the surface thereof has a plurality of projections 36 thereon which are contacted by the flames. These projections act to increase the height of the flames and cause them to extend over a greater area. The radiant element is supported in upright position concentrically of the burner chamber by legs 37 extending radially and downwardly from the wall thereof to seat upon a plurality of lugs 38 of the burner ring, the lugs 38 being supported in seats 39 of substantially bayonet-shaped slots 40 in the skirt 10 and through which the lugs are passed when removing or mounting the burner ring.

20 When the burner is in operation, the flames play upwardly of the exterior surfaces of the refractory and raise the temperature of the projections to an intense heat, which heat assures complete ignition of all the gas before discharge into the flue duct. The hot gases resulting from combustion give up their heat to the surfaces of the burner compartment and flue duct, which surfaces conduct the heat to the water within the tank. The refractory element thus not only helps to burn the gas but it increases the height of the flames of the burner relatively to the heating surfaces and it also provides radiant surfaces from 25 which heat is radiated to the wall of the heating

chamber, which radiant acts in conjunction with the direct heat of combustion to maintain a substantially higher water temperature than is normally attained with a given gas consumption. The hot gases which result from combustion of the fuel pass upwardly from the burner chamber through the flue so that substantially all of the B. t. u.'s resulting from combustion of the fuel is absorbed from the gases by the time they discharge into the vent pipe 14.

From the foregoing it is obvious that I have provided a water heater having a substantially greater heating surface and which is heated by both radiant heat and direct heat of combustion to increase efficiency of the water heater.

What I claim and desire to secure by Letters Patent is:

1. A heater of the character described including, a tank containing a liquid to be heated, means forming an open bottom burner compartment within the tank adapted to be surrounded by liquid contained in the tank, a skirt depending from and encircling the open bottom of the burner compartment and having lug engaging slots therein, a burner within said compartment and having lugs engaged in said slots to maintain the burner coaxially of the compartment, and a refractory supported over the burner.

2. A heater of the character described including, a tank containing a liquid to be heated, means forming an open bottom burner compartment within the tank adapted to be surrounded by liquid contained in the tank, a skirt depending from and encircling the open bottom of the burner compartment and having lug engaging slots therein, a burner having radial lugs engaged in said slots to support and space the burner from the skirt to provide an annular passageway for combustion supporting air, and a substantially cylindrical refractory above the burner and having legs seated upon said lugs, said refractory having projections extending into the path of flame from the burner.

3. A heater of the character described including, a tank containing a liquid to be heated, means forming an open bottom burner compartment within the tank adapted to be surrounded by said liquid, a skirt depending from the open bottom of the burner compartment and having lug engaging seats therein, a burner ring having radial lugs engaged in said seats to support the burner and having an annular refractory supporting ledge concentric with the burner compartment, and a substantially open bottom cylindrical refractory seated on said ledge and having legs seated upon said lugs, said burner having orifices arranged in circular series circumferentially of said ledge and said refractory having projections extending into the path of flame from the burner.

4. A heater of the character described including, means forming an open bottom burner compartment having a heating surface adapted to be surrounded by liquid to be heated, a skirt depending from the open bottom of the burner compartment and having lug engaging seats therein, a burner having radial lugs engaged in

said seats to support the burner and space the burner from said skirt to provide an annular air passageway therebetween, said burner having a refractory supporting ledge, and a substantially cylindrical refractory seated on said ledge and having legs seated upon the lugs, said burner having orifices located outwardly from said ledge and said refractory having projections extending into the path of flame from the burner for radiating heat to the heating surface.

5. In a water heater of the character described including a tank having an inner annular wall open at the bottom and projecting upwardly within the tank to provide a burner chamber, a flue extending upwardly within the tank and connected to the top of said wall, a burner ring spaced inwardly from said wall to provide an air passageway therebetween, radial lugs extending outwardly from the burner ring, said wall carrying supporting means for said lugs to support the burner ring and maintain the burner ring concentrically of the burner chamber, an open bottom, cylindrical refractory concentrically of the burner ring and having a cylindrical surface spaced uniformly from said wall, and legs on said cylindrical refractory engaged with parts of the burner ring to maintain concentric position of said refractory.

6. A heater of the character described including a tank for containing a liquid to be heated, a substantially cylindrical wall forming a burner compartment within the tank and adapted to be surrounded by the liquid to be contained in the tank, a substantially ring-shaped burner including a refractory support concentrically disposed with respect to and inwardly of the inner circumference of said ring-shaped burner, means supporting the burner substantially coaxially within the burner compartment, a cylindrical refractory element carried on and in contact with said support throughout the circumference thereof and having a heat radiating surface spaced from said wall to provide a flame space therebetween, said burner having jet openings into said space to direct flames in contact with said radiating surface to raise the effective height of the flames and effect direct radiation of heat of the flames on said cylindrical wall of the burner compartment.
